[57] CLAIM

The ornamental design for a transparency projector, substantially as shown and described.

DESCRIPTION

FIG. 1 is an exploded perspective view of a transparency projector, showing my new design;

FIG. 2 is a front elevational view thereof;

FIG. 3 is a rear elevational view thereof;

FIG. 4 is a left side view thereof;

FIG. 5 is a right side view thereof; and

FIG. 6 is a bottom plan view.

The transparent cover portion has been omitted from FIGS. 2-6 for convenience of illustration.

FIG. 2

FIG. 3

FIG. 4

FIG. 5

FIG. 6
